US00D875665S

(12) **United States Design Patent** (10) **Patent No.:** **US D875,665 S**
Morad et al. (45) **Date of Patent:** **** Feb. 18, 2020**

---

(54) **SOLAR PANEL**

(71) Applicant: **SUNPOWER CORPORATION**, San Jose, CA (US)

(72) Inventors: **Ratson Morad**, Palo Alto, CA (US); **Gilad Almogy**, Palo Alto, CA (US); **Itai Suez**, Santa Cruz, CA (US); **Jean Hummel**, San Carlos, CA (US); **Nathan Beckett**, Oakland, CA (US)

(73) Assignee: **SUNPOWER CORPORATION**, San Jose, CA (US)

(**) Term: **15 Years**

(21) Appl. No.: **29/674,623**

(22) Filed: **Dec. 21, 2018**

Related U.S. Application Data

(63) Continuation of application No. 29/668,612, filed on Oct. 31, 2018, which is a continuation of application No. 29/617,566, filed on Sep. 14, 2017, which is a continuation of application No. 15/359,326, filed on Nov. 22, 2016, now Pat. No. 10,090,430, which is a continuation of application No. PCT/US2015/032472, filed on May 26, 2015, which is a continuation-in-part of application No. 14/530,405, filed on Oct. 31, 2014, now Pat. No. 9,780,253, and a continuation-in-part of application No. 14/532,293, filed on Nov. 4, 2014, now abandoned, and a continuation-in-part of application No. 14/536,486, filed on Nov. 7, 2014, now abandoned, and a continuation-in-part of application No. 14/439,546, filed on Nov. 12, 2014, now abandoned, and a continuation-in-part of application No. 14/543,580, filed on Nov. 17, 2014, now Pat. No. 9,882,077, and a continuation-in-part of application No. 14/548,081, filed on Nov. 19, 2014, now abandoned, and a continuation-in-part of application No. 14/550,676, filed on Nov. 21, 2014, now abandoned, and a continuation-in-part of application No. 14/552,761, filed on Nov. 25, 2014, now

abandoned, and a continuation-in-part of application No. 14/560,577, filed on Dec. 4, 2014, now Pat. No. 9,876,132, and a continuation-in-part of application No. 14/566,278, filed on Dec. 10, 2014, now abandoned, and a continuation-in-part of application No. 14/565,820, filed on Dec. 10, 2014, now abandoned, and a continuation-in-part of application No. 14/572,206, filed on Dec. 16, 2014, now Pat. No. 9,401,451, and a continuation-in-part of application No. 14/577,593, filed on Dec. 19, 2014, now Pat. No. 9,356,184, and a continuation-in-part of application No. 14/586,025, filed on Dec. 30, 2014, and a continuation-in-part of application No. 14/585,917, filed on Dec. 30, 2014, now abandoned, and a continuation-in-part of application No. 14/594,439, filed on Jan. 12, 2015, now Pat. CLAIM

The ornamental design for a solar panel, as shown and described.

DESCRIPTION

FIG. 1 is a front, top, and right side perspective view of a first embodiment of a solar panel;

FIG. 2 is a front elevational view thereof, the rear elevational view forming no part of the claimed design;

FIG. 3 is a top plan view thereof, the bottom plan view being a mirror image of the top plan view shown;

FIG. 4 is a left side elevational view thereof, the right side elevational view being a mirror image of the left side elevational view shown;

FIG. 5 is a detail view along line 5-5 in FIG. 2 of shingled solar strips of the solar panel;

FIG. 6 is a front, top, and right side perspective view of a second embodiment of a solar panel;

FIG. 7 is a front elevational view thereof, the rear elevational view forming no part of the claimed design;

FIG. 8 is a top plan view thereof, the bottom plan view being a mirror image of the top plan view shown;

FIG. 9 is a left side elevational view thereof, the right side elevational view being a mirror image of the left side elevational view shown; and,

FIG. 10 is a detail view along line 10-10 in FIG. 7 of shingled solar strips of the solar panel.

The broken lines show portions of the solar panel that form no part of the claimed design.
